(57) **CLAIM**

The ornamental design for an ear pick, as shown and described.

DESCRIPTION

FIG. 1 is a perspective view of an ear pick showing our new design;

FIG. 2 is a front view thereof;

FIG. 3 is a back view thereof;

FIG. 4 is a left view thereof;

FIG. 5 is a right view thereof;

FIG. 6 is an enlarged top view thereof;

FIG. 7 is an enlarged bottom view thereof;

FIG. 8 is an enlarged view of the encircled area **8** of FIG. 1;FIG. 9 is an enlarged view of the encircled area **9** of FIG. 2;

and,

FIG. 10 is an enlarged view of the encircled area **10** of FIG. 2.The broken lines shown in FIG. 7 depict portions of the ear pick that form part of the claimed design. The dash-and-dot broken lines shown in the FIGS. 1, 2, **8**, **9** and **10** are included to identify areas of enlargement and form no part of the claimed design.**1 Claim, 8 Drawing Sheets**FIG. 1

FIG. 2

FIG. 3

FIG. 4

FIG. 5

FIG. 6

FIG. 7

FIG. 8

FIG. 9

FIG. 10
